UNITED STATES PATENT OFFICE.

GEORGE P. DUNCAN, OF SAN FRANCISCO, CALIFORNIA.

DESIGN FOR A CARD.

48,777.

Specification for Design.

Patented Mar. 28, 1916.

Application filed December 30, 1915. Serial No. 69,491. Term of patent 3½ years.

To all whom it may concern:

Be it known that I, GEORGE P. DUNCAN, a citizen of the United States of America, and a resident of the city and county of San Francisco, State of California, have invented a new, original, and ornamental Design for a Card, of which the following is a specification, reference being had to the accompanying drawing, forming part thereof.

The figure is a plan view of the card showing my new design.

I claim:

The ornamental design for a card as shown.

GEORGE P. DUNCAN.

Witness:

H. G. PROST.
